UNITED STATES PATENT OFFICE.

MAXEY JACKSON, OF PORTLAND, OREGON, ASSIGNOR TO THE JACKSON COMPANY, OF EMMETT, IDAHO.

LUMBER ELEVATOR.

Application filed February 9, 1920, Serial No. 357,296. Renewed June 26, 1923.

To all whom it may concern:

Be it known that I, MAXEY JACKSON, a citizen of the United States, residing at Portland, in the county of Multnomah and 5 State of Oregon, have invented new and useful Improvements in Lumber Elevators, of which the following is a specification.

This invention relates to machines for stacking or piling lumber and has for an 10 object the provision of a machine which may be easily transported from place to place, so as to be located in a convenient position for use.

Another object of the invention is the 15 provision of a lumber stacking machine, in which the lumber may be placed upon a table or support and automatically lifted therefrom and elevated to the desired height, or the operation of the machine reversed 20 so as to lower the lumber when desired.

Another object is the provision of a stacker, which is mounted upon a wheel supported truck, movable along the track and which is capable of movement in a 25 direction transversely of the track, so as to permit of the passage of cars thereover.

A further object of the invention is the provision of a power operated stacker having means for automatically stopping this 30 operation should the lumber not be removed from the carrier arms.

Other objects and advantages of the invention will appear as the following description is read in connection with the 35 accompanying drawings.

In the drawings:

Figure 1 is a side elevation of the lumber stacker constructed in accordance with the present invention.

40 Figure 2 is a plan view of the same.

Figure 3 is an end view.

Figure 4 is a vertical section on the line 4-4 of Figure 3.

45 Figure 5 is a detailed view of one of the lifting arms of the carrier.

Figure 6 is a skeleton view of the main truck.

Figure 7 is a side view of the auxiliary truck.

50 Referring to the drawings in detail, wherein like characters of reference denote corresponding parts throughout the several views.

55 In illustrating the invention, there is shown a stacker which is mounted upon a

platform 10, the said platform being carried by a frame 11 which is mounted upon wheels 12, the latter being movable over a track 13.

The platform 10 has rising therefrom 60 preferably near one side edge, standards 14. Two of these standards are shown, but it is of course obvious that their number may be increased as desired. These standards are preferably formed of angle 65 iron and are braced longitudinally of the platform by cross braces 15 and transversely of the platform by inclined braces 16, so that they are rigidly held in position. Each of the standards 14 comprise 70 vertically disposed outer members 16^a, which are arranged in pairs and spaced apart as shown, while positioned inwardly and spaced from the members 16^a is a member 17, which, together with the members 16^a provide a housing or guide for an 75 endless chain 18. This chain is composed of links 19, which are pivoted together as shown at 20, certain of said links being extended to provide laterally projecting carrier arms 21. These arms are movable vertically of the standards 14 within the space provided between the members 16^a, so as to provide a guide for the carrier arms and their outer ends are supported by 80 means of bars 22. One end of these bars are connected to one of the links 19 by means of a pivot pin 23, while their opposite ends carry a pin 24, which is movable in a slot provided in the outer end of 85 the arm 21. This provides for the proper play between the connected ends of the arm 21 and bars 22 when the chain is passing over its supporting wheels. These 90 wheels are in the form of sprocket wheels 26 and 27 respectively located at the top and bottom of the standard 14.

The lower wheels 27 are mounted upon the standard ends of a longitudinally disposed shaft 28, which is mounted in suitable bearings beneath the platform 10. This shaft has secured thereon intermediate its ends a sprocket wheel 29, which is driven from a pinion 30 mounted upon the shaft of a motor 32, the latter being suitably supported beneath the platform 10. Any other suitable motive power may be substituted for this motor. Any other suitable gearing may be substituted for connecting the shaft 28 with the motor 32, such as providing 100 105 110

ing the shaft with different speeds and suitable reversing mechanism. The gear 29 is rotatable independently of the shaft 28 but may be locked thereto by means of a 5 clutch 31 controlled by a lever 31^a, the latter being held in adjusted position by means of a dog 33.

The supporting wheels 12 are mounted upon a truck 34 and the side bars of this 10 truck are extended beyond the ends of the frame 10 so as to provide means for securing at each end thereof a transversely arranged truck 35. This last mentioned truck comprises a substantially U-shaped bar 36, 15 which is capable of vertical movement independently of the truck 34 and carries wheels 37 which are disposed at right angles to the wheels 12. The U-shaped bars 36 are guided in members 26^a carried at each end 20 of the truck 34 and are held against longitudinal movement by lugs 34^a. Depending from the bars 36 are inwardly and oppositely curved arms 35^a, which loosely support rail sections 36^b, the latter being arranged transversely of the track 13. These 25 rail sections 36^b are normally in contact with wheels 37 journaled in the U-shaped bars 36 and act to support the elevator when the rail sections are in contact with the track 13. For this purpose there is positioned transversely of each end of the truck 34, a rock shaft 38, which has secured thereto arms 39, the latter being pivotally connected to links 40 carried by the bar 36. 30 By operating the lever 41, which is connected to the shaft 38, the trucks 35 may be lowered and the truck 34 raised as shown in Figure 4. The lever 41 is held in adjusted position by a toothed segment 42. By lowering 35 the rail sections 36^b upon the track 13 and raising the truck 34 the entire device may be moved to one side of the track upon the temporary rails R shown in Figure 3, so as to permit of the passage of other cars over the track 13.

The lumber to be stacked may be unloaded from cars at each end of the elevator and for this purpose, the main truck 34 carries a table 43 which extends longitudinally along one edge of the track and is provided with openings 44 for the passage of the arms 21 of the chain 18, the lumber being lifted by these arms from the table and elevated to the desired height, 50 whereupon it is transferred to the pile. In the event of failure to remove the lumber from the arms 21 after they have reached a predetermined height, the operation of the hoisting mechanism will automatically 55 cease. To provide for this, there is located in the path of the upwardly moving lumber between the arms, an outwardly extending arm 44^a, the said arm being located upon the upper extremity of the rod 45, which is 60 mounted for longitudinal movement in a 65

bearing 46. The lower end of the arm 44^a is pivotally connected to one end of a bell crank lever 47, pivoted to a bracket 48 upon the platform 10. The other arm of this bell crank is connected by a rod 49 to the dog 33 of the operating lever 31^a. When the upwardly moving board contacts with the arm 44, the rod 45 will be lifted and through the medium of the rod 49 will move the lever 31^a to disengage the clutch 31 of the gear 29.

It is of course obvious that the elevator or hoisting mechanism may be used upon trucks other than those travelling over a track, so as to permit of its use in piling lumber in yards or other places not equipped with a railway track.

The invention is susceptible of various changes in its form, proportions and minor details of construction, and the right is reserved to make such changes as properly fall within the scope of the appended claims.

Having described the invention what is claimed is:—

1. In a lumber stacker, a wheel-supported truck and platform, lumber-moving means mounted on said platform, and transversely-arranged trucks pivotally mounted on the said first-named truck, said trucks being independently pivoted and vertically-movable independently of each other.

2. In a lumber stacker, a wheel-supported truck and platform, lumber-moving means mounted on said platform, transversely-arranged trucks pivotally mounted on the said first-named truck, said trucks being independently pivoted and vertically-movable independently of each other, and means for moving them simultaneously in opposite directions.

3. In a lumber stacker, a wheel-supported truck and platform, lumber elevating means supported by said truck and platform, and an unloading table carried by said truck and supported above the frame thereof parallel therewith.

4. In a lumber stacker, a wheel-supported truck and platform, lumber elevating means supported by said truck and platform, and an unloading table carried by said truck and supported above the frame thereof parallel therewith and having openings for the passage of the arms of the elevating means.

5. In a lumber stacker, a wheel-supported truck and platform, lumber elevating means supported by said truck and platform, a table carried by said truck parallel therewith, and means automatically actuated by direct contact of the upwardly-moving lumber for automatically stopping said elevating means in case the lumber is not removed after a predetermined height is reached.

6. In a lumber stacker, a wheel-supported truck and platform, lumber elevating means

supported by said truck and platform, a table carried by said truck parallel therewith, a transverse truck movable vertically with the main truck in opposite direction thereto, means for automatically stopping said elevating means in case the lumber is not removed after a predetermined height is reached, said means comprising a member arranged in the path of the moving lumber and a clutch controlling member operatively connected therewith.

7. In a lumber stacker, a wheel-supported platform and truck, lumber elevating means carried thereby, a member movably disposed in the path of lumber unremoved from the said elevating means, a transverse truck movable vertically with the main truck in opposite direction thereto, a motor, a controlling clutch therfor, and pivoted means interposed between said member and clutch for actuating the latter.

8. In a lumber stacker, a wheel-supported platform and truck, lumber elevating means carried thereby, a member movably disposed in the path of lumber unremoved from the said elevating means, a motor, a controlling clutch therefor, pivoted means interposed between said member and clutch for actuating the latter, and a supplemental truck arranged transversely of the first-named truck and vertically movable with relation thereto.

9. In a lumber stacker, a wheel-supported platform and truck, lumber elevating means carried thereby, a member movably disposed in the path of lumber unremoved from the said elevating means, a motor, a controlling clutch therefor, pivoted means interposed

between said member and clutch for actuating the latter, a supplemental truck arranged transversely of the first-named truck and vertically movable with relation thereto, and means on the first-named truck for lowering the transverse truck and raising the first-named truck.

10. In a lumber stacker, a wheel-supported platform and truck, lumber elevating means carried thereby, a member movably disposed in the path of lumber unremoved from the said elevating means, a motor, a controlling clutch therefor, pivoted means interposed between said member and clutch for actuating the latter, a supplemental truck arranged transversely of the first-named truck and vertically movable with relation thereto, and rail clutching members carried by the transverse truck.

11. In a lumber stacker, a wheel-supported platform and truck, lumber elevating means carried thereby, a member movably disposed in the path of lumber unremoved from the said elevating means, a motor, a controlling clutch therefor, pivoted means interposed between said member and clutch for actuating the latter, a supplemental truck arranged transversely of the first-named truck and vertically movable with relation thereto, and means on the first-named truck for lowering the transverse truck and raising the first-named truck, said transverse truck embodying inverted U-shaped bars guided on means on the main truck and carrying said rail clutching members.

In testimony whereof I affix my signature.

MAXEY JACKSON.
